US0D1096668S

(12) **United States Design Patent** (10) **Patent No.:** **US D1,096,668 S**
(45) **Date of Patent:** **** Oct. 7, 2025**

(54) **ENCLOSURE**

(71) Applicant: **L&H Industrial, Inc.**, Gillette, WY
(US)

(72) Inventor: **Gage Wandler**, Tempe, AZ (US)

(73) Assignee: **L&H Industrial, Inc.**, Gillette, WY
(US)

(**) Term: **15 Years**

(21) Appl. No.: **29/893,226**

(22) Filed: **May 26, 2023**

(51) **LOC (15) Cl.** **13-03**

(52) **U.S. Cl.**

USPC **D13/184**; D13/162

(57) **CLAIM**

The ornamental design for a enclosure, as shown and described.

DESCRIPTION

FIG. 1 is a front perspective view of an enclosure illustrating our new design;

FIG. 2 is a front elevation view of the enclosure of FIG. 1; FIG. 3 is a rear elevation view of the enclosure of FIG. 1; FIG. 4 is a right side elevation view of the enclosure of FIG. 1;

FIG. 5 is a left side elevation view of the enclosure of FIG. 1;

FIG. 6 is a top plan view of the enclosure of FIG. 1; and, FIG. 7 is a bottom plan view of the enclosure of FIG. 1. In the above-referenced drawings, the broken lines illustrate merely the environment and form no part of the claimed design.

1 Claim, 7 Drawing Sheets
